PROJECTION LAMP

Edward W. Kellogg, Moorestown, N. J., assignor,
by mesne assignments, to Radio Corporation of
America, New York, N. Y., a corporation of
Delaware

Application August 15, 1934, Serial No. 739,880

12 Claims. (Cl. 176—123)

This invention relates to projection lamps, and more particularly to a lamp adapted for use in sound recording and reproducing apparatus employing photographic sound records, and for other purposes for which high intrinsic brilliancy as well as freedom from rapid fluctuations is desired.

In making a photographic record of sound, fluctuations in the source cause irregularities in the exposure of different parts of the film, and these irregularities result in noise when the record is reproduced. Likewise, fluctuations in the light source employed in the reproducing equipment result in noise. Fluctuations which, owing to the persistence of vision, are not objectionable for strictly visual purposes, may be very objectionable in such lamp applications as I have mentioned. For this reason, arc lamps are not satisfactory, and the only lamps which have been found entirely suitable for such purposes have been those employing incandescent filaments, operated either on direct current or on alternating current of much higher frequency than the usual 50 to 60 cycles per second.

Operation of incandescent lamps on alternating current results in temperature fluctuation at double the frequency of the current alternations. The higher the frequency the smaller are the fluctuations in temperature and consequently in luminosity. Likewise, for a given frequency, the heavier the filament wire the smaller are fluctuations in temperature. This is because the thermal energy stored in the hot metal is greater for a given rate of energy radiation in the heavy filament wire than in a thin wire wherein the ratio of radiating surface to cross section of wire is greater than in a heavy wire.

Where requirements in regard to freedom from fluctuation are not extremely rigid, low voltage, high current lamps operated on 60 cycle alternating current have been employed, and by going to sufficiently heavy filaments the fluctuations can be reduced to any required degree. However, it has not proved practical to go far enough in this direction to give really satisfactory operation. If the filament is designed to operate at less than about six volts, it becomes so short that an excessive fraction of the heat generated within it is carried by metallic heat conduction to the supporting wires. With a minimum practical voltage, high current necessarily means high wattage, and this calls for large bulbs and more ventilation. Were another material having the high boiling and melting points of tungsten but having much higher resistivity available, the de-

sired thick filament lamp might be designed, but in the absence of such materials, it appears that the only solution is in supplying the power in some other manner than by ohmic resistance to the flow of current through the metal.

Among the lamps heretofore proposed for picture projection purposes, there are some in which the light radiating body is heated by electron bombardment instead of by passage of current. This permits the radiating body to be made in the form of a small, compact bead or button of tungsten instead of an elongated conductor, and such a button will store enough heat to reduce temperature fluctuations to so small a magnitude that they are not objectionable. A lamp of this type, if exhausted to high vacuum, would, for a short period, offer the advantages of the lamp which is the subject matter of my present invention. Such a high vacuum lamp would be provided with an electron emitting cathode, and the incandescent bead or button would be connected to a source of voltage by which it can be made positive with respect to the cathode. The lamp could be operated on either direct or alternating current, and in the latter case would rectify its own current. A high vacuum lamp, however, is open to the objection that the part of the bulb nearest the light radiating body becomes blackened in a very short time. The presence of an inert gas in sufficient pressure not only reduces the evaporation of the tungsten from the hot electrode, but, by convection, carries the tungsten vapor to the top of the bulb instead of permitting it to travel straight to the nearest glass surface. In view of this important advantage of operating high intensity lamps in a gas, such lamps of the type just described as have found any considerable use are of the gas filled rather than of the high vacuum type. The presence of the gas, however, changes the mode of conduction between the cathode and the anode from what would be a pure electron stream in a high vacuum lamp to a luminous arc through ionized gas. While satisfactory for picture projection purposes, such lamps are not satisfactory for sound recording or reproduction because the arc stream, although partially hidden by the electrode, contributes a considerable amount to the light which enters the sound optical system, and since the arc luminosity is far from steady, noise results.

The primary object of my invention is to provide a lamp of the type in which the incandescent body is heated by electron bombardment which

will be suitable for use in sound recording and reproducing apparatus.

A further object of my invention is to provide an improved projection lamp of the type set forth 5 wherein the arc is so confined that it will not interfere with or contribute anything to the light emitted by the lamp in the useful direction.

Still a further object of my invention is to provide a projection lamp of the type set forth which 10 can be operated on either D. C. or A. C., which will provide a high intensity source, and which will not give rise to hum when used for sound recording or reproducing purposes.

Aside from the fact that the lamps now practically available for sound recording and reproducing purposes cannot be satisfactorily operated on alternating current owing to cyclic temperature fluctuations of the filament, the present 15 lamps have several other drawbacks. Optical systems for use in sound equipment utilize, in general, only so much of the light emitted by the source as can be collected by a condensing lens. The light which reaches the sensitive element, whether it be film or photocell, is further restricted 20 by apertures which, from one or another design consideration, are restricted to small size. Usually (and this involves placing the condenser lens close to the source) the image of the source 25 can be made large enough to more than cover or fill the aforementioned small aperture. When this condition is met, there is no gain in useful light by employing a larger source. Increase in 30 the amount of useful light is possible only by increasing the concentration of the light, or, in other words, by employing a source which emits more light from a given superficial or projected area. This can be done in several ways, all of 35 which may be realized in my invention, by using a solid or continuous source, by raising the temperature, and by increasing the emissivity. The 40 spaces between the turns of a coiled filament obviously contribute nothing to the light radiated in a given direction. A solid block of tungsten of the same outside dimensions and at the same 45 temperature would radiate more light, and the lamp which is the subject of the present invention utilizes such a solid block as its radiating element. The thick block of tungsten can also be 50 worked at a higher temperature than a slender filament without causing short life due to a burn-out. Polished tungsten emits much less light per unit of surface area than a black body at the same temperature. If, however, the surface 55 is made very rough, as, for example, by numerous closely spaced relatively deep pits, the emissivity of the tungsten can be increased so as to approach that of a black body. The same object is attained in some measure by a single pit or concavity. The interior surfaces of the pits 60 transmit light in the useful direction not only by virtue of their own temperature, but also by reflecting light which they receive from other nearby surfaces. Such roughening of the surface is 65 evidently not feasible in the case of a filament, but may readily be applied to a block or button, heated by electron bombardment.

Another object of my invention, therefore, is to provide a lamp in which the radiating body appears as a solid or continuous area of incandescent material.

Another object of my invention is to provide a lamp in which the radiating body may be worked at higher temperature than is practical with lamps of the incandescent filament type of moderate current rating.

Still another object of my invention is to provide a lamp in which the light emitting surface is roughened in such a manner that an approach to black body radiation is attained.

In certain optical systems it is important that 5 the image of the source, as produced by the condenser or other lenses, shall be as nearly as possible uniformly bright over the entire area utilized. This can obviously not be attained with lamps of the coiled filament type, but can be 10 realized with a lamp of the type involved in my invention. For such special applications the roughening or pitting would be either dispensed with, leaving a plane uniform surface, or a method of roughening employed which produces very 15 fine irregularities, as, for example, etching or fine sand blasting. The minute variations in luminosity from point to point would then not be detectable in the optical image of the source, owing to the aberrations and imperfect focusing of the 20 lens or lenses.

Another object of my invention, therefore, is to provide a lamp adapted for use where a source of 25 exceptional uniformity throughout its projected area is desired.

A further object of my invention is to provide an improved projection lamp which has greater power efficiency than those heretofore used.

Still another object of my invention is to provide an improved projection lamp which will be 30 small and compact and which will need less ventilation than lamps previously used.

In accordance with my invention, I provide a lamp in which a small rod or button of tungsten 35 is heated to incandescence by electron bombardment from a filament associated therewith, and I place a third electrode in such a position relative to the tungsten electrode that it acts as a shield to prevent the arc from interfering with the light emitted by the incandescent button in the useful 40 direction. In accomplishing this, it is necessary not only to hide the main body of the arc from visibility from the direction of the optical system, but to strictly exclude the arc and all streamers from it or gaseous conduction of all kinds from 45 the region in front of the incandescent electrode.

The novel features that I consider characteristic of my invention are set forth with particularity in the appended claims. The invention itself, however, both as to its organization and method 50 of operation, together with additional objects and advantages thereof, will best be understood from the following description of several embodiments thereof when taken in connection with the accompanying drawing in which

Figure 1 is a central section of one form of my invention showing the nature and the relation of the various electrodes thereof.

Fig. 2 is a sectional view taken along the line II-II of Figure 1 with circuit connections to 60 the lamp.

Fig. 3 is a detail view of a modified form of the invention, and

Figs. 4 and 5 show further modifications of my invention.

Referring more in detail to the drawing, wherein similar reference characters designate corresponding parts throughout, there is shown an envelope 1 which may be either highly evacuated or filled with a suitable inert gas. Disposed within the envelope 1 are three electrodes comprising a filamentary cathode 3, a shielding electrode 7, and an electrode 5 which, on direct current operation, is the anode, and which I shall hereafter call the anode, although when the lamp is op- 70 75

erated on alternating current, as hereinafter described, the electrode 5 may actually become a cathode during a part of the cycle.

The cathode 3 may be connected through the conductor leads 9 to any suitable source of current, as, for example, a low voltage battery or, as is usually more convenient where an alternating current supply of electrical power is available, to the secondary 11a of transformer 11, the primary of which is connected to the electric lighting mains. In the particular circuit shown in Figure 2, the anode 5 is maintained positive with respect to the cathode 3 by means of a battery 14 connected between a mid-tap of the transformer secondary 11a and the anode 5 through conductor 13, while the shielding electrode 7 is maintained at a negative potential through conductor 17 by means of a battery or the like 15.

As shown in Figures 1 and 2, the shielding electrode 7 comprises a disc-like plate provided with an aperture 19 substantially centrally thereof and through which the tungsten button or anode 5 extends, the plate 7 being held in position by the conductor lead 17, which is heavy enough to serve 25 as a satisfactory support, and lying in a plane normal to that of the arc between the electrodes 3 and 5 but outside of the arc path. The anode 5 extends through the aperture 19 and is supported in place by substantially radially extending wires 21 which are connected to the conductor lead 13, shown bent into a loop 13a and anchored on both sides of the loop, while the cathode 3 is supported in spaced relation to the anode 5 by means of the conductor leads 9. The anode 5 may be provided on the side toward the cathode with an enlarged head 5a, the purpose of which will be presently explained. The other end of the anode 5, or the end facing in the direction in which useful light is radiated (arrow A, Figure 1), has its radiating surface increased in some suitable manner, as by making it concave, grooved, or pitted. It is shown in the drawing as having a number of small closely spaced pits, 5b, deep relative to their diameters.

In Fig. 3, I have shown a modified form of the invention in which the shield 7, which may be of metal, such as tungsten, has been extended by the addition of an approximately spherical portion 23, which serves to reflect back to the anode 5, a large fraction of the energy radiated by the back surface. This radiation serves no useful purpose, and not only makes it necessary to supply more energy to the anode to keep it hot, and incidentally makes it necessary to dissipate more heat through the surface of the bulb or envelope, but also makes more external shielding of the lamp necessary to protect eyes of operators, and keep down stray light. The reflector 23 can be either incorporated as part of the arc guard 7, or it may be a separate member. Since it would not have to be raised to as high a temperature as the anode, it would not have to be made of as refractory a metal as tungsten, but a more highly reflecting metal can be used.

I have also illustrated, in connection with Fig. 3, a circuit which may be used for operation of the arc on alternating current, the alternating voltage being derived from an extra secondary winding 24a of the power transformer 24. The cathode is heated by alternating current as in Fig. 2, but with the circuit shown in Fig. 3, the electrode 5 would not be maintained continuously positive with respect to the filament 3, but alternately positive and negative. During the period 75 of reversed voltage, there would be a reverse

current, but aside from the fact that the reversed arc imparts less heat to the electrode 5 than an equal current in the direction which makes electrode 5 an anode, the reverse current is not objectionable. The magnitudes of the arc current in the two directions would depend upon the voltage and on the resistance 18, upon the electron emission of the two electrodes in view of their respective sizes, temperatures, and materials, and in some measure on the form of the electric field as determined by the shapes and positions of all these electrodes. If the arc is operated on alternating instead of direct current, the heat imparted to the electrode 5 will no longer be continuous, but pulsating, each half cycle supplying a pulse of heat and those produced by the positive half cycles being greater than those produced by the negative half cycles. This irregular supply of heat means that the temperature of the anode cannot be maintained strictly 20 constant, but herein lies the advantage of this form of lamp as compared with one of the incandescent filament type. Owing to the thickness of the electrode 5 or its large mass compared with its radiating surface, it constitutes a large reservoir of thermal energy and cools down very 25 slightly during the periods in which it is receiving less energy than it is radiating. Therefore, although there will be fluctuations in radiation, they will be small enough to be unobjectionable whereas lamps of the filament type would have equally small fluctuations in brightness only in the case of lamps of extremely high current ratings which, practically, means also very high wattage ratings.

An object close to an arc stream and not connected through solid conductors to either of the electrodes tends to become negatively charged, owing to the great mobility of the free electrons in the arc, as compared with the positive ions. 35 The guard 7 would, therefore, assume a negative potential if it were simply allowed to float, or seek its own potential, or in other words, if it were not connected to the remainder of the circuit. This would mean simply omitting battery 15, resistance 16, and conductor 17. The negatively charged guard 7 would still be efficacious in confining the arc to the back of the electrode 5. This makes the requirements for operating the lamp entirely on alternating current extremely 40 simple, namely a transformer with suitable windings to supply the filament current and the arc current, and a ballast resistance or reactor connected in circuit with the arc. The battery 15 has been included in the illustrations simply to 45 show how such a battery or source of bias voltage would be connected if, for special reason, it should be found necessary or desirable to maintain the guard at a greater negative voltage than that which it would assume if floating. If the 50 lamp is to be operated with the shield 7 floating or insulated from the electrodes, the shield 7 would itself not need to be necessarily of conducting material, although it should obviously be opaque, since its function is both to strictly limit 55 the arc to one side of the anode and to exclude from the optical system any light originating in the arc. From the foregoing explanations, it will be seen that the front surface of the anode 5 constitutes a source of light in which all the factors making for maximum radiation in the useful 60 direction from a source of limited area can be brought to their optimum values. There are no dark holes or waste spaces, the anode may 65 be raised, by regulating the value of the arc cur- 70 75

rent, to as high a temperature as tungsten will stand without melting or excessive evaporation, and the roughening of the surface increases the specific brightness in a marked degree. The heat is, of course, generated at the back surface of the anode and radiated at the front, but the heat conductivity of the tungsten is so high that there would be only a small temperature drop between the two faces.

10 It would be possible to provide two cathodes, with a special shield between them, and operate the lamp like a full wave rectifier. The purpose of such an arrangement would be to insure equal impulses of heat during the two halves of the 15 A. C. cycle, and thereby still further reduce temperature fluctuations on A. C. operation.

The annular opening around the anode would, of course, permit a certain amount of light from the arc to pass. Such light, however, would not 20 get through the optical system if this is suitably designed. Only such light as is directed within the core subtended by the condensing lens 25 can enter the optical system, and if the mask 27 is slightly smaller than the image of the anode, the 25 mask will exclude any possible light which might come from the surrounding annular crack. In order to reduce the possibility of appreciable light entering the optical system from this source, the anode is shown as having an enlarged head 30 5a. Fig. 4 shows an alternative arrangement wherein the forward or pitted end of the anode is enlarged to serve the same purpose. Another arrangement is illustrated in Fig. 5, in which a mask 29 is provided in front of the anode 5 to 35 hide the edges of the anode, around which some light from the arc might otherwise enter the optical system. In Fig. 5, the mask 29 is shown as constituting part of the supporting structure for the anode 5, but the mask might equally well 40 be an independent member. It would, in general, be mounted as close to the anode as feasible. The wire or wires 21 which support the anode are preferably located on the side of the shield 7 away from the filament 3. This insures that the 45 arc will not strike to the wires. If a single supporting wire carried the anode 5, it would have to be much heavier than the three radiating wires shown, or of greater cross section than the aggregate cross section of the three small wires, in 50 order to provide an equally rigid support. The heat carried away by supporting wires is directly proportional to their cross section. Hence, a support of the form shown in the drawing is preferable to a single wire support.

55 For certain optical arrangements, a circular source of light is not the most advantageous. It is obvious that the shape of the anode and the corresponding hole in the shield 7 may be made to suit the specific purpose. For example, if a 60 long narrow slit is to be illuminated, it might be desirable to accomplish this by forming an image of the anode in the plane of the slit. For such purpose, the anode might advantageously be made 65 rectangular and provided with a groove parallel to the longer axis. The bottom of the groove, which would be the brightest part of the anode, would then be imaged on the slit.

In other applications, it may be desired to form 70 an image of a definite shape, as for example a triangle, and of the best possible uniformity. In present practice, this is attained by special arrangements of lenses and a mask, whereas it can be accomplished very much more simply when using the lamp which is the subject of this 75 invention, by suitably shaping the aperture in

the mask 29 of Fig. 5, and adapting the shape and surface of the anode to correspond. This feature could be incorporated in a high vacuum lamp as well as in a gas-filled lamp.

Although I have shown and described several 5 specific embodiments of my invention, I am fully aware that many modifications thereof and changes therein are possible. I therefore desire that my invention shall not be limited except insofar as is necessitated by the prior art and 10 by the spirit of the appended claims.

I claim as my invention:

1. In an electrical discharge device, a pair of electrodes adapted to have an arc maintained therebetween, and means in close proximity to 15 only one of said electrodes for preventing said arc from being visible from one side of said last named electrode.

2. In an electrical discharge device, a pair of electrodes adapted to have an arc maintained 20 therebetween, and means surrounding only one of said electrodes for preventing said arc from being visible from one side of said last named electrode.

3. In an electrical discharge device, a pair of electrodes adapted to have an arc maintained therebetween, one of said electrodes having an enlarged head portion, and a third electrode of opaque material having an opening therein, said one electrode extending through said opening, and 25 said opening having a smaller diameter than said enlarged head portion whereby said third electrode serves to prevent said arc from being visible from the side thereof opposite to the one 30 facing the arc.

4. In a lamp in which the source of useful light comprises a small body of refractory material adapted to be heated to incandescence by means of an electrical arc, a shielding member of opaque material arranged about said body in a 40 plane normal to that of the arc for preventing the arc from being visible from the direction of useful light radiation.

5. In a lamp in which the source of useful light comprises a small body of refractory material adapted to be heated to incandescence by means of an electrical arc, a shielding member of opaque material surrounding said body in spaced 45 relation to the arc path for preventing the arc from being visible from the direction of useful 50 light radiation.

6. In a projection lamp, a filamentary cathode, an anode adapted to be heated to incandescence by an electrical arc from said cathode and to serve as a source of useful light, and a shield 55 of opaque material surrounding said anode outside of the arc path for preventing said arc from being visible from the direction of useful light radiation.

7. The invention set forth in claim 6 characterized in that the anode is roughened at the end thereof facing the direction of useful light radiation.

8. The invention set forth in claim 6 characterized in that the anode has one end thereof concave and that said concave end faces in the direction of useful light radiation.

9. The invention set forth in claim 6 characterized in that the anode is made of refractory material and characterized further in that the end 70 thereof facing in the direction of useful light radiation is concave to said direction.

10. The invention set forth in claim 6 characterized in that said anode is made of refractory material and characterized further in 75

that said lamp comprises a gas filled envelope whereby to make high operating temperatures feasible and to prevent blackening of the envelope.

5 11. The invention set forth in claim 6 characterized in that said anode is made of tungsten.

12. The invention set forth in claim 6 characterized by the addition of a reflector on the arc side of said shield for reflecting radiant energy emitted by the incandescent anode in directions other than the direction of useful light 5 radiation back onto said anode.

EDWARD W. KELLOGG.
